LOOM LET-OFF

BACKGROUND OF THE INVENTION

The invention relates to an improved positive let-off mechanism for looms of the type adapted to weave tightly woven fabrics such as duck or the like and in particular pertains to a mechanism that is easily and accurately set up to obtain the desired amount of crimp in the fabric as it is formed.

Known mechanisms of the prior art that are adapted to control the amount of crimp in woven fabric are considered quite complex and require what is considered considerable time to accurately set them up to obtain the desired amount of crimp as well as to select and assemble the plurality of elements required for a single condition. These mechanisms utilize a compound gearing arrangement consisting of a combination of worm wheels, spur and change gears and to increase or decrease the percentage of crimp, this gearing arrangement must be disassembled and then the proper combination selected for assembly thereto.

The let-off mechanism according to the instant invention utilizes a permanent gearing arrangement and by simply changing a cam controlled ratchet wheel which transmits the required motion to said gearing arrangement, or on some occasions the drive or driven sprocket, any desired percentage of crimp is quickly and accurately obtained.

SUMMARY OF THE INVENTION

The let-off mechanism of the present invention is actuated intermittently by a cam member fixed on and adapted to rotate with the loom's crankshaft. By means of a cam follower and cooperating linkages a ratchet wheel is intermittently rotated to provide input motion to a housed gearing arrangement fixed to the framework of a loom. The gearing output motion rotates a sprocket member which in turn is in driving relation with sprocket members fixed on the ends of a pair of rollers that are intermittently rotated for drawing the warp yarns from the warp beam. A braking device is adapted to function in cooperation with the warp beam and provides the required drag on said warp beam so as to maintain a desired amount of tension on the warp yarns as the latter are being withdrawn by the above-mentioned rollers.

It is an object of the invention to provide an improved warp let-off mechanism for a loom in which the percentage of crimp formed in the woven fabric can be simply and accurately controlled and which can be increased or decreased as desired with a minimum number of parts and downtime of the loom.

BRIEF DESCRIPTION OF THE DRAWING

FIG. 1 is a view in side elevation of a portion of a loom showing the mechanism according to the invention applied thereto.

FIG. 2 is a plan view of the mechanism shown in FIG. 1.

FIG. 3 is a view in end elevation of the warp beam braking device as seen looking from the front of the loom.

FIG. 4 is a view in end elevation and partially in section of the gearing arrangement for transmitting motion to the rollers which draw the warp yarn from the warp beam, and FIG. 5 is an end view partially in section of the gearing arrangement shown in FIG. 4.

DESCRIPTION OF THE PREFERRED EMBODIMENT

Referring to the drawings wherein only as much of conventional loom structure is depicted as is necessary to a complete understanding of the invention, there is shown in FIG. 1 a portion of the left-hand loomsides 10 having a combined driven and drag roll support stand 11 fixedly attached thereto by means of bolts 12 and 13.

A crankshaft 14 (FIG. 1) extends between the loomsides in the usual manner and the left-hand end thereof which extends outwardly beyond the loomsides 10 has a cam member 15 fixed thereon for rotation with said crankshaft.

The support stand 11 has a gear box 16 (FIGS. 1, 4 and 5) attached by any suitable means (not shown) to the side thereof which includes a lower motion input shaft 17 and an upper motion output shaft 18. As shown in FIGS. 4 and 5, the gearing arrangement within the gear box 16 includes a bevel gear 19 that is fixed on and adapted to rotate with shaft 17. Bevel gear 19 is in driving relation with a second bevel gear 20 the latter of which is assembled on the lower end of a drive shaft 21. This drive shaft is supported vertically within the gear box 16 and has fixed thereon adjacent its upper end a worm gear 22. Worm gear 22 is in driving relation with a worm wheel 23, the latter of which assembles on shaft 18 and which is rotated according to the dictates of the motion input shaft 17.

Shaft 17 extends outwardly from the gear box 16 as shown at 24 in FIG. 4 and immediately adjacent to said box has pivotably assembled thereon at a point intermediate its ends a pawl support arm 25. (FIG. 1). This support arm carries at its upper end a pivotable pawl member 26 that is engageable with teeth 27 of a ratchet wheel 28. Ratchet wheel 28 assembles on shaft 17 and is adapted to intermittently rotate the latter in a manner now to be described.

The pawl support arm 25 adjacent its lower end has one end of a drive rod 29 pivotably attached thereto as at 30 and the opposite end thereof is pivotably and adjustably attached by means of a bolt 31 to a cam follower support arm 32 (FIG. 1). The cam follower support arm is pivotably supported by means of a bolt 33 on a bracket 34 which is attached to the loomsides 10 by bolts 35. This support arm includes an arcuated slot 36 through which bolt 31 extends and permits adjustment of the forward end of drive rod 29 within the limits of said slot. An integrally formed and laterally extending lug 37 is disposed at the forward upper side of the support arm and provides a means for assembly of a rotatable cam follower 38 thereto.

The cam follower 38 is adapted to track on the outer periphery of the rotating cam member 15 and is held in contact therewith by means of a coil spring 39. One end of this coil spring 39 attaches to the lower end of the pawl support arm 25 as at 40 and the opposite end is attached to a spring bracket 41 the latter of which is fastened to the loomsides 10 by any suitable means.

It can be easily seen that drive rod 29 is caused to reciprocate when the support arm is pivoted to and fro by means of the motion created by cam member 15 and the cam follower 38. This reciprocating movement oscillates the pawl support arm 25 and the pawl member 26 carried on the upper end thereof engages each tooth of the ratchet wheel 28 successively and intermittently rotates the latter in the direction of the indicating arrow 42 as shown in FIG. 1.

The intermittent rotary movement of the ratchet wheel is transmitted through the gearing arrangement to a drive sprocket 43 which is fixed on that portion of the motion output shaft 18 that extends outwardly from the gear box 16.

As shown in FIGS. 1 and 2, the support stand 11 is provided with an integrally formed and rearwardly extending arm 44 which is adapted to rotatably support one end of a pair of spaced parallel driven rolls 45 and 46 by means of their gudgeons 47 and 48 being journaled in integrally formed housings 49 and 50 respectively. It should be understood that the opposite ends of these driven rolls are provided with similar gudgeons and are rotatably supported in a like manner by a support stand that is attached to the right-hand loomsides not shown.

Gudgeons 47 and 48 extend outwardly beyond their respective housings 49 and 50 and have fixed thereon aligned sprocket members 51 and 52 that are interconnected by a sprocket chain 53.

Gudgeon 48 extends outwardly for a greater distance than gudgeon 47 and has a driven sprocket 54 fixed thereon immediately adjacent to sprocket member 52. A sprocket chain 55 interconnects the driven sprocket 54 with the drive sprocket 43 and causes the intermittent rotary movement of the latter to be transmitted to the driven rolls 45 and 46.

In FIG. 1 the warp yarn is depicted by numeral 56 and the yarn beam about which it is wrapped by numeral 57. Like the driven rolls 45 and 46 the yarn beam 57 includes gudgeons for its support and the left hand only being shown in FIG. 1 is identified by numeral 58. A yarn beam bearing 59 supports the yarn beam for rotary movement and is assembled to the lower rearward end of the loomside 10 by means of bolts 59' and nuts 60.

A pair of drag roll brackets 61 and 62 (FIGS. 1 and 2) are attached to the inner side of the support stand 11 by means of bolts 63 and 64, respectively. Bracket 61 supports the end of a drag roll 65 and bracket 62 the end of a drag roll 66. These drag rolls are horizontally disposed and positioned in spaced and parallel relation. Drag roll 65 is supported intermediate the driven rolls 45 and 46 and drag roll 66 forward of the driven roll 46. Additionally, the drag roll brackets 61 and 62 are vertically adjustable allowing the drag rolls 65 and 66 to be raised or lowered whereby the amount of wrap of the warp yarn 56 about the driven rolls can be increased or decreased as best suited for a particular weaving condition.

The support stand 11 further includes an integrally formed and upwardly directed bracket element 67 (FIGS. 1 and 2) the inner surface of which provides a means for supporting the ends of an additional pair of drag rolls 68 and 69 having mounting plates 70 and 71, respectively, fixedly attached to the ends thereof. These additional drag rolls are disposed generally one above the other and the lower one 68 being approximately twice the diameter of the upper roll 69 is fixed to the bracket element 67 by means of bolts 72.

The upper drag roll 69 is radially adjustable relative to its companion roll 68 so as to permit an increase or decrease in the area of contact by the warp yarn on the outer surface of said roll 68. This upper drag roll is attached to bracket element 69 by means of bolts 73 and by means of a pair of arcuated slots 74 and 75 in the mounting plate 70 through which said bolts pass, the roll 69 can be moved to any desired position within the limits of said slots.

The warp yarn 56 as shown in FIG. 1 is drawn from the warp beam 57 by the driven rolls 45 and 46 which may have any suitable type of covering, such as rubber, to increase traction and prevent slippage thereon of said warp yarns. The warp beam is rotatable, and to maintain tension on the warp yarn 56 as it is drawn from the beam, it is necessary that a braking device be provided to produce a drag on the beam. The braking device may be of any desired type and the one shown in FIGS. 1 and 2 is of the caliper type such as furnished by H. H. Products Division of Kelsey Hayes Co. of 8601 N. 43rd Street, Milwaukee, Wisconsin.

A disc 76 is fixed on gudgeon 58 intermediate the yarn beam 57 and the yarn beam bearing 59. The braking device is identified generally in FIGS. 1 and 2 by numeral 77 and includes opposed spring biased plates 78 and 79 with the opposed faces thereof having arcuated brake elements or so-called pucks 80 and 81 fixed thereon. A portion of the disc passes between the pucks as it is caused to rotate with the yarn beam and said pucks are caused to bear against the sides thereof thereby producing a drag on the yarn beam. The means for applying and releasing this braking force includes a cam-type lever 82 having an adjustable spring tensioned actuating rod 83 pivotally connected at one end thereto. The opposite end of this actuating rod is mechanically linked to a double armed lever 84 that is rockable to apply or release the braking force by means of a pivotable brake lever 85.

In operation, the warp yarn is drawn from the warp beam intermittently by the driven rolls 45 and 46 which receive their intermittent rotary motion through their driving connections

with the gear box 16. The cam member 15 which rotates continuously on the loom's crankshaft and which provides the intermittent motion to the gear box 16 can be timed and set to actuate the elements cooperating therewith, at any degree of rotation of said crankshaft. This feature is considered advantageous because, relative to the takeup and beat up of the loom, the warp yarn can be let-off at the most feasible time for any particular weaving condition.

The warp yarn is held under the desired amount of tension as it is drawn from the warp beam by means of the braking device adapted to function in cooperation therewith. The warp yarn passes over the top of the driven rolls 45 and 46 and beneath the drag rolls 65 and 66 disposed immediately adjacent to said driven rolls.

After leaving drag roll 66 as shown in FIG. 1 the warp yarn passes over the top and forward portion of drag roll 69 and thence downwardly around the back and lower portion of drag roll 68. The combination of drag rolls 68 and 69 is instrumental in preventing a loss in yarn tension in the driving area during the time of filling yarn beat up. After leaving drag roll 68, the warp yarn is advanced through the usual stop motion device and harness frames not shown.

I claim:

1. A positive warp let-off mechanism for a loom having a rotatably driven shaft member and a warp beam upon which a multiplicity of warp yarns are wound, the improvement which comprises:

- a. a pair of spaced and horizontally disposed driven rolls for drawing the warp yarns from said warp beam;
- b. a first pair of drag rolls disposed adjacent said driven rolls for increasing the area of surface contact of said warp yarns thereon;
- c. a second pair of drag rolls spaced from said driven rolls for maintaining tension on said warp yarns;
- d. a drive sprocket interconnected by chain members to said driven rolls;
- e. cam actuated drive means for intermittently rotating said drive sprocket and driven rolls to advance said warp yarns in timed relation to the loom's fabric takeup mechanism; and
- f. a braking means functioning in cooperation with said warp beam for maintaining desired tension on said warp yarns as they are drawn from the warp beam.

2. The warp let-off mechanism according to claim 1 wherein said cam actuated drive means includes a gear box for rotating said drive sprocket and a ratchet wheel for transmitting intermittent rotary motion through said gear box to said drive sprocket.

3. The warp let-off mechanism according to claim 2 wherein said drive means further includes a cam fixed on and for rotation with said rotatably driven shaft member and a cam follower with interconnecting linkages for transmitting the dictates of said cam to said ratchet wheel.

4. The warp let-off mechanism according to claim 3 wherein said interconnecting linkages comprise:

- a. a pivotable pawl engageable with the outer periphery of said ratchet wheel;
- b. a pawl support arm oscillatably carried by said gear box in axial alignment with said ratchet wheel; and
- c. a drive rod interconnecting said support arm with a lever carrying said cam follower for transmitting intermittent indications from said cam to said ratchet wheel.

5. The warp let-off mechanism according to claim 4 wherein said support arm includes a biasing means for maintaining said cam follower in contact with the outer periphery of said cam.
